UNITED STATES PATENT OFFICE.

CHRISTIAN MILLER, OF CHICAGO, ILLINOIS.

STATION-INDICATOR.

No. 885,503.

Specification of Letters Patent. Patented April 21, 1908.

Application filed July 9, 1907. Serial No. 382,923.

To all whom it may concern:

Be it known that I, CHRISTIAN MILLER, citizen of the United States, residing at Chicago, in the county of Cook and State of Illinois, have invented certain new and useful Improvements in Station-Indicators, of which the following is a specification.

This invention is a station indicator or timing mechanism, by means of which the 10 motorman or engineer of a car or train may have before him a schedule or indicator adapted to be applied to a clock, for the purpose of showing the time he starts on a run and the times he should arrive at the various 15 intersecting streets, stations or other places, as well as indicating in connection with the clock the time he actually arrives at said places, and whether he is ahead or behind time, and if so, how much.

20 The invention includes an ordinary clock, to the face of which is applied an indicating dial with the names of the streets, stations or other places marked thereon, this dial being made of glass, and placed in front of the 25 clock dial, and corresponding therewith to the extent that the marks indicative of the stations are placed on the additional dial a distance apart corresponding to the space in minutes, as indicated on the clock dial for 30 the run from one station to another.

The additional or indicating dial provided by my invention is capable of being turned with respect to the clock face, so that the starting point may be placed at any desired 35 time with respect to the clock dial, according to the time of starting.

The invention is illustrated in the accompanying drawings, in which

Figure 1 is a face view of the device. Fig. 40 2 is a side elevation thereof. Fig. 3 is a partial section on the lines 3—3 of Fig. 1.

Referring specifically to the drawings, a clock, as a whole, is indicated at 6, and it may be of any suitable construction, and 45 needs no further description, except that it has a circular outer casing 7 around which is a circumferential rib 8, and at the front edge of which is a circumferential outwardly projecting flange 9.

50 The clock is supported upon a bracket 10 which may be secured to any fixed part and which has a band 11 adapted to fit around the clock case, and this band is provided with a bead 12 which receives the rib 8 on the

clock case. The band may be loosened or 55 tightened by a thumb screw 13, and it is of proper size and shape to hold the clock, and when the band is tightened the clock is held therein by the engagement of the rib 8 and the bead 12. This permits the clock to be 60 turned in the band, but prevents it from dropping or falling out.

Mounted in front of the face of the clock is a glass indicating dial or transparent disk 14, held in a ring frame 15. This dial has a series of marks 16, indicating various streets or stations, and located a proper distance apart according to the number of minutes between each station, corresponding in this respect to the minute spaces of the clock dial. 70

The ring 15 is held to the clock casing by means of a pair of clips 17 which engage the flange 9. Said flange has a series of holes 18 extending around the same at a distance apart corresponding, say, to a minute space 75 on the clock face. The ring 15 has two or more rearwardly projecting pins 19 which are adapted to enter these holes, and by which the position of the ring and the indicating dial carried thereby is fixed with respect to the clock dial. By unfastening the 80 clips 17 and disengaging the pins 19 the ring 15 and the glass dial carried thereby may be turned to bring the mark of the starting point opposite the desired minute mark on 85 the clock face. Then, the rest of the marks on the indicating dial will occupy the proper relation with respect to the times at which the car or train should arrive at the other stations marked on the indicating dial, and 90 on reaching any particular station the hands of the clock will indicate the time of arrival at each station, and, by reference to the indicating dial, whether it is ahead of or behind the right time. The whole clock may be 95 turned in the band if desired, to bring the marks in convenient position to be read.

By means of the indicating device shown a motorman or engineer may be provided with a clock on which the stations will be indicated with respect to time, and which can be set at the beginning of each trip and changed for a subsequent trip, always indicating, however, the schedule time of the various stations when set at the proper starting time 105 or point.

No modification of the interior mechanism of the clock is necessary, and with slight

modifications the indicating device may be applied to any kind of a time piece.

I claim:

The combination of a clock, the case of which has an exterior circumferential outwardly-projecting flange with a series of holes around the same, a ring in front of the clock and having pins adapted to enter said holes and clips engageable with the flange,

and a transparent dial in the ring and covering the face of the clock, the dial having station marks thereon. 10

In testimony whereof I affix my signature, in presence of two witnesses.

CHRISTIAN MILLER.
